UNITED STATES PATENT OFFICE.

FREDERICK H. PERRY, OF BEVERLY, MASSACHUSETTS, ASSIGNOR, BY MESNE ASSIGNMENTS, TO UNITED SHOE MACHINERY CORPORATION, OF PATERSON, NEW JERSEY, A CORPORATION OF NEW JERSEY.

INSOLE-MACHINE.

1,285,357.

Specification of Letters Patent. Patented Nov. 19, 1918.

Application filed March 12, 1917. Serial No. 154,187.

To all whom it may concern:

Be it known that I, FREDERICK H. PERRY, a citizen of the United States, residing at Beverly, in the county of Essex and State 5 of Massachusetts, have invented certain new and useful Improvements in Insole-Machines; and I do hereby declare the following to be a full, clear, and exact description of the invention, such as will enable others 10 skilled in the art to which it appertains to make and use the same.

This invention relates to machines for operating on soles and more particularly to the performance of certain operations upon 15 insoles.

In the manufacture of certain types of insoles it is desirable to perform an operation upon the rib of the insole by which it is set in an inclined position with respect to the 20 body of the insole. In the case of a reinforced insole, such an operation is performed at the same time usually, although not necessarily, as when performing the rib 25 tightening operation on the insole. Such operations, and other operations of more or less similar character, are performed by machines having instrumentalities which engage and press against the opposite surfaces of the rib, and in certain of such 30 machines the operation of these instrumentalities is progressive and intermittent.

The present invention relates to machines of the type and for the purposes just set forth, and one object of the invention is to 35 produce a machine of simple construction and compact form, and particularly a machine in which the actuating mechanisms are of a simple and direct character and are located, for the most part, below and in the 40 rear of the work-support upon which the insole rests during the operation thereon.

Another object of the invention, relating 45 particularly to its use in connection with reinforced soles, is to provide simple and effective means for trimming the reinforcing 50 material. In order to prevent the reinforcing material on a Gein insole from being visible in the finished shoe, it is desirable to trim the material, particularly at the 55 shank-portion of the insole, to a line on the feather within the edge of the insole. In

the machine of the present invention it is proposed to employ reciprocating work-engaging members for feeding the work intermittently, and to provide a trimming cutter 55 for the reinforcing material which is so mounted as to reciprocate with the feeding instrumentalities. From this arrangement it results that the cutter moves with the work during the feeding movement, 60 while its operation is performed during the return movement of the feeding instrumentalities and while the work is held stationary by means provided for that purpose. Consequently, although the cutter operates with 65 a dragging action, it does not impede the intermittent feeding movement, since its operation is timed to alternate with the feeding movement.

Other objects of the invention, the advantages of which will be readily recognized by those skilled in the art, will be set forth in connection with the description of the preferred embodiment of the invention.

To the accomplishment of the above objects the invention comprises the features and combination of parts hereinafter described and defined in the appended claims.

The preferred embodiment of the invention is illustrated in the accompanying drawings in which Figure 1 is a side elevation, 80 partly in vertical section; Fig. 2 is a partial side elevation showing certain of the operative instrumentalities in a position other than that shown in Fig. 1; Fig. 3 is a plan 85 view of the machine; and Fig. 4 is a detail view, in section, on the line 4-4 of Fig. 1.

The invention is illustrated as embodied in a machine adapted particularly for rib-tightening or perfecting reinforced insoles 90 of the Gein type, the perfecting operation herein consisting in pressing the reinforcing material, usually canvas or duck, firmly into the angles between the rib and the body and feather of the insole, and in bending 95 the rib to, and setting it in, an inwardly-inclined position.

As shown in Figs. 1 and 3, the insole upon which the machine operates comprises the usual body-portion 6, having a rib produced by an integral upturned lip 8 and a marginal feather 10. This insole is rein-

forced by canvas 12, which is connected in place and extends over the lip and the adjacent surfaces of the body and the feather.

The instrumentalities of the machine include a work-support 14, in the form of a disk, with a horizontal flat surface upon which the insole rests. This disk is fixed on the upper end of a stem 16 which slides vertically, and rotates, in a stationary sleeve 18. This sleeve is integral with a housing-member 20, which serves as a frame and also an inclosure for the actuating mechanism of the machine, being mounted at the upper end of a column 22 of convenient form and height.

The work support is pressed upwardly by a spring 24 which is coiled within the sleeve 18 and around a rod 26. The rod is concentric with, and fixed to, the stem 16, and it slides through a centrally perforated stop-screw 30 which is threaded into the sleeve 18. The rod is provided with adjustable stop-nuts 28 which coöperate with the screw 30 to limit the upward movement of the work-support under the influence of the spring, when no work is in the machine. To facilitate the introduction of an insole the rod 26 may be connected with operating means such as a treadle (not shown) by which the work-support may be depressed in the usual manner.

The lip-forming tools comprise a member 32 which engages the inner surface of the lip and acts as an anvil, and a member 34 which engages the outer surface of the lip and acts as a hammer by which the lip is bent and compressed against the anvil. It will be observed from Fig. 2 that when the lip is pressed between the lip engaging faces of the two tools 32 and 34 it is bent to an inwardly-inclined position, the pressure extending from the base to the crown and being sufficient to set the lip in this position.

For the purpose of trimming the margin 45 of the reinforcing canvas 12 the machine is provided with a knife 36.

The anvil 32 and the hammer 34 are employed as means for feeding the work intermittently, and for this purpose they are so mounted as to swing about a vertical axis in the rear of the work-support. A carriage 38 is mounted within an upper housing-member 42 which is removably fixed upon the lower housing-member 20. The carriage is provided with a horizontal circular flange 40 which rests upon the upper surface of the housing-member 20 and fits in a correspondingly formed opening in the member 42, so that a bearing is provided on which the carriage may be oscillated about the axis of the flange 40. The carriage is held down against the bearing just described by engagement with the upper part of the housing-member 42, as shown in dotted lines in Fig. 1, and it is centered, at

its upper end, by means of a pivot-stud 44 fixed in the housing and entering a recess in the top of the carriage.

The hammer is mounted upon a slide 46 which moves in a circularly curved guideway 47 formed in the carriage 38. The center of the curvature of this guideway is located below, and slightly in the rear of, the work-support, so that when the hammer is actuated by the movement of the slide in the guideway its operative extremity moves toward and from the lip of the insole in a path which is slightly inclined in a forward and downward direction. When the carriage is oscillated about its vertical axis the hammer is reciprocated, through a short arc, about such axis for the purpose of imparting a feed-movement to the insole through the engagement of the hammer with the lip of the insole. In order that it may participate in the same function, the anvil is mounted in a forward projection from the carriage, as will be described.

For the purpose of actuating the slide 46 and the hammer, the lower end of the slide 90 is connected, by a ball-and-socket joint 48, with an eccentric-strap 50 which embraces an eccentric 52. This eccentric is actuated by a power-shaft 53, and the shaft is journaled in bearings in the lower housing-member 20, and provided with a pulley 56 through which it may be connected with any suitable source of power. By these means a constant and rapid reciprocation of slight amplitude is imparted to the slide 100 and the hammer, causing the latter to move into and out of engagement with the lip of the insole. In order to provide for operating upon insoles having lips of different thicknesses, the hammer is adjustably connected with the slide by means of a binding-screw 58, which is threaded in the slide and passes through an elongated opening in the shank of the hammer, and this shank is seated in a close-fitting recess in the slide, 110 this recess being concentric with the slide so as to limit the adjusting movement to a circularly-curved path concentric with the slide.

The lip-forming tool 32 has a cylindrical shank 60 which slides vertically in a sleeve 62, and this sleeve is integral with a forward projection from the carriage 38, so that the oscillating movements of the latter cause the tool 32 to participate in the work-feeding movement of the hammer. The tool 32 is supported rigidly, by the sleeve 62, against the pressure due to the impact of the hammer, but by vertical movement of the shank in the sleeve the tool is permitted 125 to accommodate itself to insoles of various thicknesses.

During the lip-forming and feeding operations the tool 32 is forced downwardly against the work by spring pressure, as 130

shown in Fig. 1. For this purpose a leaf spring 64 is employed, this spring being articulated, at its forward end, to the shank 60, while its rear end is fixed to a lever 66 which is mounted on a pivot 68 on the carriage.

During the idle return movement of the tools following each feed movement the pressure of the tool 32 against the insole, as shown in Fig. 2, is released. For this purpose the lever 66 is connected, by a link 70, with a pivot-screw 72 on the slide 46, so that at each retracting movement of the slide and the hammer the lever is rocked in a direction to release the tension of the spring 64. In order to insure the entire release of the pressure of the tool against the insole the lever is provided with a forwardly-extending arm 74 of which the end comes into engagement with the lower surface of the spring when the lever is moved to its extreme position, and thus, through the intermediation of the spring, the tool 32 is lifted a short distance clear of the work. This distance is, or may be, so slight, however, as not to be distinguishable in the drawings, a lift of a small part of an inch being sufficient to insure the release of the work from compression.

When the hammer is retracted and the anvil is raised, as just described, it is necessary to prevent the insole from being forced upwardly by the spring 24 of the work support, and also to retain the insole securely in position during the return movement of the tools. For this purpose a presser-foot 76 is employed. This presser-foot is pivoted, by a stud 78, on a bracket 80 which is fixed in stationary position on the housing. Integral with the presser-foot is a depending arm 82 which carries a roller 84. The roller cooperates with a cam 86 fixed on the power-shaft 53, and is maintained in engagement therewith by a spring 88 attached to the arm 82. The cam is formed to permit the spring to swing the arm rearwardly, and thus depress the presser-foot to operative engagement with the feather of the insole, at the completion of each lip-forming and feeding operation, and the presser-foot remains so depressed until the lip-forming tools have completed their return movement and again engaged and gripped the work, whereupon the cam 86 acts to swing the presser-foot upwardly, out of engagement with the work, so as to permit the latter to be fed freely.

The canvas-trimming cutter 36 is mounted adjustably upon the carriage by its dove-tail shank, which is fixed in vertical position, by means of a clamp-plate 90 and a screw 92, against a bracket 94 which is fixed, in turn, by means of a screw 95, to the forward portion of the carriage 38. The cutter may be adjusted vertically upon loosening the screw 92, so as to set it to cut only to the required

depth to completely sever the canvas without mutilating the feather. The bracket 94 has a horizontal rib-and-groove connection with the carriage, as shown in Fig. 4, so that it may be adjusted forwardly and rearwardly thereon to decrease or increase the distance of the knife from the lip. Such an adjustinent will vary the distance of the cut from the edge of the insole, it being remembered that the insole is guided by its rib which lies at varying distances from the edge of the insole. The knife is preferably set so as to engage the canvas at a distance, from the lip, approximately equal to the width of the narrower portions of the feather, so that at the shank portion of the insole, where the feather is widest, the cut will come well within the edge, thus insuring that the canvas shall not be visible in the finished shoe. With such an adjustment of the parts it will be observed that in case the canvas already has been trimmed flush with the insole edge when the insole is brought to the present machine, the knife 36 performs its function only at the shank.

Owing to the fact that the trimming cutter is mounted on the carriage, it oscillates with the lip forming and insole feeding tools, and consequently its cutting operation is performed during the return movement of the latter. Accordingly, the drag of the knife upon the work occurs while the work is held stationary, between the work-support and the presser foot, and this arrangement has the advantage that the operation of the knife does not resist the intermittent feed movement of the insole. Furthermore, the cutting edge of the knife being directed away from the presser-foot provides for a clean severance, that is, there is no opportunity for the fabric to buckle as would be the case if the cutting stroke were toward the point where the insole is clamped.

The oscillatory feeding movement of the carriage is produced by cam mechanism. For this purpose a block 96 is pivoted to the bottom of the flange 40, and is embraced by a forked cam lever 98 which rocks upon a pivot-stud 100 in the housing of the machine, as shown in dotted lines in Fig. 3. The cam lever carries a roller 102 which engages a cam 104 fixed on the power-shaft 53. At each rotation of the shaft, accordingly, the carriage is swung once in each direction to produce a feed movement at each cycle of operations.

While the invention has been described as embodied in a machine adapted particularly for perfecting reinforced soles, it will be understood that it is useful also in, and applicable to, sole machines for performing various other more or less similar operations, and that the invention is not, in general, limited to the details of construction and operation of the embodiment hereinbe-

fore described and illustrated in the accompanying drawings.

The invention, and the preferred means for practising it, having been thus described, 5 it is definitely stated in its true scope in the following claims.

What is claimed as new is:—

1. A sole machine having, in combination, a work support; an inside forming tool arranged to engage the inner surface of the rib of a sole on the support; a hammer for engaging the outer surface of the rib; a spring for pressing said tool toward the support; and means for relieving the spring-pressure, 10 intermittently, while the hammer is out of engagement with the rib.
2. A sole machine having, in combination, a work support; an inside forming tool arranged to engage the inner surface of the 15 rib of a sole on the support; a hammer for engaging the outer surface of the rib; means for pressing said tool toward the support; means for relieving such pressure intermittently, while the hammer is out of engagement, 20 with the rib; and means for moving the hammer and said tool laterally, while in engagement with the rib, to feed the sole.
3. A sole machine having, in combination, a spring-pressed work support; an inside 25 forming tool arranged to engage the inner surface of the rib of a sole on the support; a hammer for engaging the outer surface of the rib, means, for controlling and supporting said tool, constructed and arranged to 30 press said tool toward the support while the hammer is in engagement with the rib and to relieve such pressure while the hammer is out of engagement with the rib; and means for engaging the sole, to resist the pressure 35 of the support, intermittently while the hammer is in its retracted position.
4. A sole machine having, in combination, a work support; a hammer adapted to engage the rib of a sole on the support; a slide 40 on which the hammer is mounted; a guideway, for said slide, curved about a center located below the surface of the support; and means for reciprocating said slide to actuate the hammer.
5. A sole machine having, in combination, a work support; a carriage mounted to turn about an upright axis beside the support and provided with a guideway; a slide arranged 45 to move in said guideway; a hammer carried by the slide and arranged to engage the rib of a sole on the support; means for reciprocating the slide in the guideway to actuate the hammer; and means for oscillating the carriage, while the hammer is in engagement 50 with the sole, to feed the latter.
6. A sole machine having, in combination, a work support; a carriage mounted to turn about an upright axis beside the support and provided with a guideway; a slide mounted 55 in the guideway; a tool carried by the slide

and adapted to operate upon a sole on the support; a shaft; and actuating members carried by the shaft and connected with the slide and the carriage, respectively, to actuate them in suitable time relation.

7. A machine for operating on reinforced soles having, in combination, tools arranged and actuated to grip the sole intermittently; means for reciprocating the tools so as to feed the sole while so gripped; means for retaining the sole against retrograde movement during the return movement of said tools; and a cutter for trimming the reinforcing material movable laterally with said tools so as to be idle during the feed movement but to act on the reinforcing material during the return movement of the tools.

8. A machine for operating on reinforced soles having, in combination, means for feeding a sole intermittently; a cutter for trimming the reinforcing material; and means for reciprocating said cutter, in the line of feed, so as to move it in unison with the work during the feed movements, and in the opposite direction during the intervening dwells of the work.

9. A machine for operating on reinforced soles having, in combination, a work support, reciprocatory means for feeding the insole, and a cutter arranged to trim the reinforcing material where it lies on the feather on a line within the edge of the insole at the shank portion at least, said cutter being mounted to reciprocate with said feeding means.

10. A machine for operating on reinforced insoles having, in combination, means for supporting the insole, means for feeding the insole including an intermittently operated, reciprocatory gripper mechanism and a presser foot to hold the insole from movement when the gripper mechanism is released, and a cutter for incising the reinforcing material on a line within the edge of the insole at the shank portion at least, mounted to reciprocate with the gripper mechanism.

11. A machine for operating on reinforced insoles having, in combination, a work support, a step-by-step feed mechanism, means for clamping the feather of the insole against the work support to hold the insole from retrograde movement between the feed steps, and a fabric trimming cutter mounted for movement with the feed mechanism, arranged at the rear of the clamp in the line of feed, said cutter having its cutting edge directed away from the clamp.

12. A machine for operating on reinforced insoles having, in combination, means for supporting, feeding and operating on the insole at its marginal portion including a clamp mechanism intermittently operated to engage the insole and hold it from movement, and a fabric trimming knife arranged

to trim the fabric where it lies on the feather on a line within the edge of the insole at the shank portion at least.

13. A machine for operating on reinforced insoles having, in combination, a work support, a step-by-step feed mechanism, a reciprocatory knife for trimming the reinforcing material along a line on the feather, and means controlled by the feed mechanism for reciprocating the knife.

14. A machine for operating on reinforced insoles having, in combination, a work support, a step-by-step feed mechanism, a knife for trimming the reinforcing material along a line on the feather constructed and arranged to trim the reinforcing material step-by-step in the intervals between the advance movements of the feed mechanism, and actuating means for said feed mechanism and said knife.

15. A machine for operating on reinforced insoles having, in combination, a work support, a reciprocatory feed mechanism, a re-

ciprocatory knife for trimming the reinforcing material along a line on the feather, and 25 a single means for actuating said feed mechanism and said knife.

16. A sole machine, having, in combination, a work support; an inside forming tool continuously engaging the inner surface of the rib of a sole on the support; an outside forming tool intermittently engaging the outer surface of the rib; means for pressing the inside tool toward said support; and means for relieving such pressure during the periods when the outside tool is disengaged from the rib.

17. A sole machine, having, in combination, a work support; an inside forming tool; means for pressing said tool toward the support; a reciprocating outside forming tool movable toward and from the rib; and means controlled by the retracting stroke of the outside forming tool for relieving the pressure on the inside tool.
